(57) **CLAIM**

The ornamental design for a fluid dispenser, as shown and described.

DESCRIPTION

FIG. 1 is a three-dimensional view of the fluid dispenser with cap.

FIG. 2 is a front view of the fluid dispenser of FIG. 1.

FIG. 3 is a back view of the fluid dispenser of FIG. 1.

FIG. 4 is a side view of the fluid dispenser of FIG. 1.

FIG. 5 is a side view of the fluid dispenser of FIG. 1.

FIG. 6 is a top view of the fluid dispenser of FIG. 1; and,

FIG. 7 is a bottom view of the fluid dispenser of FIG. 1. The broken line showing of elements of a fluid dispenser depicts environment and forms no part of the claim.
